WORKPIECE GUIDE FOR TABLE SAWS

James H. Nadeau, 271 Zion St.,
Hartford, Conn. 06106

Filed Apr. 14, 1972, Ser. No. 244,332

Term of patent 14 years

Int. Cl. D15—09; D8—05
U.S. Cl. D54—13 R

FIG. 1

FIG. 2

FIG. 3

FIG. 4

FIG. 5

FIG. 6

FIG. 7

FIG. 1 is a perspective view of a workpiece guide for table saws showing my new design;

FIG. 2 is a top plan view thereof;

FIG. 3 is a front elevation thereof;

FIG. 4 is a rear elevation thereof;

FIG. 5 is a right end elevation thereof;

FIG. 6 is a left end elevation thereof;

FIG. 7 is a bottom plan view thereof.

I claim:

The ornamental design for a workpiece guide for table saws, as shown and described.
